UNITED STATES PATENT OFFICE.

RUTH A. LE GRAND, OF WILKES-BARRE, PENNSYLVANIA.

DESIGN FOR A DOLL.

Application filed March 1, 1922. Serial No. 954. Term of patent 3½ years.

To all whom it may concern:

Be it known that I, RUTH A. LE GRAND, and a citizen of the United States, residing at Wilkes-Barre, in the county of Luzerne and State of Pennsylvania, have invented a new, original, and ornamental Design for a Doll, as shown in the accompanying drawing and described in the following specification.

I claim:

The ornamental design for a doll as shown.

RUTH A. LE GRAND.
